Primary Examiner—Harold A. Dixon**[57] ABSTRACT**

A sample of blood to be tested for the presence of biological activity is added to a suitable growth medium which includes a C¹⁴ containing carbon source fermentable to produce gaseous C¹⁴O₂. After a suitable incubation period, a portion of the gaseous atmosphere above the medium is analyzed for the presence of radioactivity. In the improvement herein described, mammalian cells in the blood sample are lysed in order to reduce background reading when the radioactivity is measured and to provide a better signal-to-noise ratio.

DETECTION OF BIOLOGICAL ACTIVITY

DESCRIPTION OF THE INVENTION

This invention is directed to an improved means for 5 the detection of biological activity in blood.

Biological activity in blood, such as bacteremia (bacteria in blood), in the past, presented a difficult detection problem. Culturing was done manually and, of course, was a tedious procedure that required considerable periods of time until the physical presence of bacteria, fungi, or other microorganisms could be detected.

More recently, a radiometric technique for the detection of biological activity in the blood has undergone 15 clinical testing and has been adopted for commercial practice. In that method samples of blood are inoculated into a suitable growth medium that includes a C¹⁴ containing carbon source, the inoculated medium is incubated for a suitable period, and a portion of the gaseous atmosphere is analyzed for C¹⁴O₂ while in the gaseous state. Such process is described, *inter alia*, in U.S. Pat. No. 3,676,679 issued July 11, 1972; and in the articles "Early Detection of Bacterial Growth, with Carbon¹⁴-Labeled Glucose," *Radiology*, 92, No. 1, pp. 154-5 (January 1969); "Automated Radiometric Detection of Bacterial Growth in Blood Cultures," *J. Labs. Clin. Med.*, 75, No. 3, pp. 529-34 (March 1970); and "Automated Radiometric Detection of Bacteria in 2,967 Blood Cultures," *Applied Microbiology*, 22, No. 5, pp. 846-849 (November 1971). A commercial instrument for the practice of a rapid, automated process is available under the trademark Bactec (Johnston Laboratories, Inc.).

In practicing the process for the gaseous detection of the C¹⁴O₂, a general background reading of about five units is frequently encountered. It has also been generally observed when the gas from a sample inoculated with blood is tested, the background reading generally is increased by 10 to 15 units. In other words, even when the blood sample is from a patient who has no microbial infection, the radioactivity will read, on the average, between about 15 and 20 units. The gas from the blood sample of a patient with bacteremia or the like, of course, provides an even higher reading. Generally, a reading of about 30 units or more is used as an indication of microorganisms in the blood sample.

Reference to units, herein, is to units of the Bactec instrument. One hundred units are equal to 0.025 microcuries of C¹⁴ activity.

While the described system has proven effective for the rapid detection of biological activity in the blood and is in commercial use, the background reading of the inoculated sample provides a rather low signal-to-noise ratio and a rather high threshold signal level.

It is an object of this invention to increase the signal-to-noise ratio when blood is screened for the presence of biological activity.

It is a further object of this invention to reduce the background reading in the gas measurement of the C¹⁴O₂ when blood is screened for the presence of biological activity.

This invention is directed to the process of detecting biological activity in the blood wherein:

- a. a growth medium including a C¹⁴ containing carbon source which is fermentable to produce carbon dioxide is inoculated with a blood sample;

b. the inoculated sample is exposed to conditions conducive to the occurrence of normal metabolic processes for a period of time sufficient to cause production of carbon dioxide by the fermenting of said source; and

c. at least a portion of the gaseous atmosphere from said fermentation is measured for radioactivity to determine the presence of C¹⁴O₂. The improvement, according to the present invention, comprises lysing mammalian cells present in said blood sample whereby the background noise for the measurement of gaseous C¹⁴O₂ is reduced.

The precise reason for the increased background noise due to components in the blood is not fully understood. Whatever the cause, it has been discovered that the background reading is significantly decreased if the mammalian cells are lysed before being allowed to ferment the substrates in the test medium. In some tests, the background noise due to the blood was almost cut in half. By decreasing the background noise due to blood, the signal-to-noise ratio is improved and the threshold level for detection of microbes may be reduced.

Further information regarding the process to which this invention relates and the apparatus for carrying out the process is contained, *inter alia*, in U.S. Pat. No. 3,676,679; *Radiology*, 92, No. 1, pp. 154-5 (January 1969), *J. Labs. Clin. Med.*, 75, No. 3, pp. 529-34 (March 1970), *Applied Microbiology*, 22, No. 5, pp. 846-849 (November 1971), JLI 604, JLI 609A, JLI 610A, JLI 611, and JLI 612.

Generally, the process employs a nutrient medium that contains water, a suitable C¹⁴ containing carbon

35 source, a nitrogen source, minerals and trace elements. Typical C¹⁴ containing carbon sources may be glucose, sucrose, fructose, galactose, mannose, rhamnose or the like, phenylalanine lysine, arginine, or the like, carboxylic acids such as citric acid or the like, glycerol, or urea. Glucose, which is readily available, constitutes a preferred material. Generally, the level of radioactivity

40 will vary from about 0.1 to about 10 microcuries per 10 ml of medium. The assimilable nitrogen source may be either organic or inorganic, such as nitrates, nitrites,

45 ammonia, urea, amino acids, or the like, while minerals such as chlorides, sulfates or phosphates of calcium, sodium, potassium, magnesium or the like and trace elements such as manganese, iron, zinc, cobalt or the like, may be employed. Vitamins, cofactors or other enrichment agents such as anti-coagulants may also be added if desired. Finally, the medium may also include a buffer for pH adjustment and maintenance. The atmosphere above the culture medium can be air, oxygen,

50 or the like if aerobic tests are being conducted, whereas nitrogen, CO₂, or the like can be employed if anaerobic tests are being conducted.

The medium is described in detail in the above publications and particularly in U.S. Pat. No. 3,676,679, JLI 611, and JLI 612. While the patent indicates that up to 20 percent or more carbohydrate may be employed in the medium, preferred media are said to contain only up to about 0.001 percent carbohydrate and commercial media do contain such small amounts of carbohydrate added as such. In addition, if the media contains peptone, yeast extract, or the like, an additional 1 percent or so of carbohydrates may be present as a component of this additive. The media normally has a dis-

solved solids content of about 2.5 percent to about 3.5 percent by weight.

Vials containing media for aerobic cultures, designated No. 6A, and vials containing media for anaerobic cultures, designated No. 7A, are commercially available from Johnston Laboratories, Inc. A medium suitable for aerobic fermentation may contain tryptic soy broth, hemin, menadione, sodium polyanethol sulfonate, and C¹⁴-labeled substrates, while a medium suitable for anaerobic culture may contain tryptic soy broth, yeast extract, hemin, menadione, L-cysteine, sodium polyanethol sulfonate and C¹⁴-labeled substrates. The 30 ml of medium in the 50 ml vials has a radioactivity of about 1.5 microcuries. Commercial media have a pH of about 7.3.

Most frequently the sample of blood will be added to the medium in amounts ranging from about 0.5 to about 10 percent by volume and the inoculated medium can be cultured under agitation at temperatures between about 20°C and about 60°C and most often between about 33°C and about 39°C. The length of time for the culture will depend, inter alia, on the amount of inoculum employed and the particular microorganism involved. Tests have demonstrated that microorganisms generally will create a positive response in time periods ranging from 1 to 24 hours.

After a suitable period of time, e.g., 8 hours, the gaseous atmosphere over the culture medium is tested for radioactivity. Employing this invention, readings of about 20 to 25 units or more generally will indicate the presence of biological activity in the blood. The threshold reading will, of course, depend in part on the background noise due to the general surroundings. Such noise can readily be determined by testing the atmosphere from a medium that has not been inoculated. The reading used to indicate the presence of microorganisms may vary somewhat depending on the level of general background noise. When the threshold level has been reached, the sample is considered positive. Negative samples are further incubated and tested again to insure against the presence of slow growing microorganisms.

In accordance with the improvement of this invention, the mammalian cells of the blood sample, that is red cells, white cells, and platelets are lysed before substantial incubation has occurred. The cells may be lysed by contacting them with cold water, by contacting them with chemicals or by subjecting them to physical disruption. Lysis desirably is accomplished prior to inoculation but may also take place during the early stages of incubation; e.g., during the first hour or so of incubation.

In order to lyse cells with water, the blood sample is added to water until the cells disrupt. The rate of lysis depends both upon water temperature and dilution, with lower temperatures and greater dilutions providing better lysis. For example, deionized sterile water at 0°C will lyse cells more rapidly than the same water at room temperature. The lower temperature may provide twice the cell disruption as room temperature. Similarly, a sample dilution of 1:5 will result in more rapid lysis than a sample dilution of 1:1. Generally, sufficient water will be employed to provide as sample: water weight ratio of at least about 1:1, with the maximum amount of water being a matter of choice. Temperatures employed for the lysis most often will range from about 0°C to about 40°C.

Lysis with water may, of course, be carried out as a separate step before inoculation and incubation. Lysis may also be accomplished, however, by adding the blood sample to a dilute culture medium. A normal culture medium may contain about 2.5 - 3 percent dissolved solids in purified water and this medium does not lyse cells. A medium containing less than about 1 percent dissolved solids, however, will induce lysis to a significant degree. Media containing from about 0.5 percent to about 1 percent dissolved solids are preferred if lysis is to take place in the media.

As an alternate method of lysis, chemicals may be employed and generally are used at low concentrations (e.g., on the order of 0.1 percent) and for short contact periods. Typical chemicals include nonionic detergents, such as saponin, polyoxyethylene sorbitan, and the like. While the chemical can be added to the sample as a separate step, it may be desirable to incorporate the chemical into the syringe employed to draw the blood sample from the patient. In the syringe the blood cells are treated with the chemical at a suitable concentration (such as, for example, 0.1 percent by weight) to effect lysis and when the sample from the syringe is added to the culture medium, the sample is diluted and the concentration of the chemical reduced. Care must be taken to avoid too high concentrations, too powerful chemicals, or too long contact times or all cells, including microbial cells, will be substantially lysed. The selection of agents and treating conditions are within the skill of the art.

The use of physical means to lyse mammalian cells includes, inter alia, ultrasonic vibration, and the like.

The above methods to lyse cells are known to the art, and, therefore, will not be described further here.

It is not necessary to effect lysis of all mammalian cells, since the lysis of cells provide progressive improvement as the percentage of cells lysed increases. Preferably, lysis will be conducted to disrupt sufficient mammalian cells to reduce the background reading due to the sample by at least about 30 percent and, in a particularly preferred embodiment, lysis will be carried out so as to reduce the background reading due to the blood sample by at least about 50 percent. It is evident that lysis should not be so severe as to destroy microbial cells that may be present in the mixture. Mammalian cells are fragile and generally are more sensitive to lysis than bacteria, fungi and the like. Selective lysis of mammalian cells is within the skill of the routinist.

The following examples are included in order to illustrate the practice of this invention. These examples are included for illustrative purposes only and in no way are intended to limit the scope of the invention.

EXAMPLE 1

Blood was drawn from 11 patients for use in this experiment. One 3 ml portion of each sample was injected into 30 ml of culture medium in a 50 ml vial, (No. 6A, Johnston Laboratories, Inc.) while a second 3 ml portion was added to 3 ml of sterile water at about 0°C to partially lyse the cells. After a few minutes (3-5 minutes) the second portion (now 6 ml of volume) was also added to 30 ml of the same type of culture medium (No. 6A) in a 50 ml vial. The culture medium contained tryptic soy broth, hemin, menadione, sodium polyanethol sulfonate and C¹⁴-labeled substrates and was characterized by pH of 7.3 ± 0.2.

All samples were cultured at 35°C and the radioactivity of the gaseous atmosphere over the culture medium was checked initially at 3-hour intervals and later at 24-hour intervals. Two of the 11 samples proved to contain bacteria, while the remaining nine were sterile. For the nine that were sterile, the maximum value for radioactivity (Growth Index) in the gaseous portion over the medium, as recorded on a Bactec instrument, is shown in Table 1 below:

TABLE 1

Patient	A	B	C	D	E	F	G	H	I
Normal blood (N)	20	22	20	28	23	23	32	18	25
Lysed blood (L)	18	15	14	24	17	14	19	12	20
(N - L)	2	7	6	4	6	9	13	4	5

As the above table demonstrates, the lysed blood samples in each case provide lower background noise than the normal samples.

The average peak index for the normal blood sample was 23.4 units while the average peak index for the lysed blood sample was 17.0 units. Other tests in fluids that contained no cells indicated a general instrumental background noise level of 10 on the day that the tests of this example were conducted. Therefore, the background noise due to normal blood was 13.4, (23.4 - 10.0), whereas the background noise for the lysed blood samples was 7.0, (17.0 - 10.0). The treatment of this example, therefore, reduced the background noise due to the blood about by a factor of 2.

EXAMPLE 2

A medium of 10 ml of tryptic soy broth containing 0.04 microcuries of C¹⁴ glucose was inoculated with 1 ml of sterile blood, and compared to the same medium containing various concentrations of chemical lysing agents. The results are shown in Table 2 below:

TABLE 2

Treatment	Maximum Growth Index
Control	100
10% polyoxyethylene sorbitan	44
1% do	46
0.1% do	89
0.1% saponin	42
0.01% saponin	89

Ps. aeruginosa and Staph. epidermidis were inoculated into JLI 6A vials and into JLI 6A vial containing 0.1 percent saponin. The detection times and maximum Growth Index were not affected by this treat-

5
ment.

Since modification of this invention will be apparent to those skilled in the art, it is intended that this invention be limited only by the scope of the appended claims.

I claim:

1. In the process of detecting biological activity in blood wherein:

- a. a growth medium including a C¹⁴ containing carbon source which is fermentable to produce carbon dioxide is inoculated with a blood sample;
  - b. the inoculated sample is exposed to conditions conducive to the occurrence of normal metabolic processes for a period of time sufficient to cause production of carbon dioxide by the fermenting of said source; and
  - c. at least a portion of the gaseous atmosphere from said fermentation is measured for radioactivity to determine the presence of C¹⁴O₂, the improvement comprising lysing mammalian cells present in said blood sample before the sample is exposed for a substantial period of time to conditions conducive to the occurrence of normal metabolic processes, whereby the background noise for the measurement of radioactivity of gaseous C¹⁴O₂ is reduced.
2. The process of claim 1 wherein the cells are lysed by mixing the blood with water prior to inoculation of the growth medium.
3. The process of claim 1 wherein the cells are lysed by admixing the blood with a dilute growth medium containing less than about 1 percent by weight of dissolved solids.
4. The process of claim 1 wherein the cells are lysed with a chemical.
- 45 5. The process of claim 1 wherein the cells are subjected to physical treatment to lyse them.
6. The process of claim 1 wherein the treatment reduces the background noise due to the blood sample by at least about 30 percent.
- 50 7. The process of claim 1 wherein the treatment reduces the background noise due to the blood sample by at least about 50 percent.
